ATTORNEY.

UNITED STATES PATENT OFFICE.

JOHN SAURER, OF ORRVILLE, OHIO.

BAG-HOLDER.

SPECIFICATION forming part of Letters Patent No. 363,172, dated May 17, 1887.

Application filed October 1, 1886. Ser'l No. 215,055. (No model.)

To all whom it may concern:

Be it known that I, JOHN SAURER, a citizen of the United States, residing at Orrville, in the county of Wayne and State of Ohio, have 5 invented certain new and useful Improvements in Bag-Holders, of which the following is a specification.

My invention relates to a bag-holder, and is illustrated in the accompanying drawings, in 10 which—

Figure 1 is a plan view of the bag holder. Fig. 2 is a side elevation of the holder, showing it supporting a bag. Figs. 3 and 4 are views, separately, of the two bag-supporting 15 arms. Fig. 5 is a view of one of the bag-mouth spreaders.

The letter A designates a base or stand of any suitable shape or construction, and b an upright post or standard fixed to the said base. 20 The upper part, b', of this post is round, and the two bag-supporting arms C are pivoted on this round part, and are vertically adjustable thereon—that is, they may be moved up or down.

25 The bag-supporting arms C, at their pivoted ends, are "halved" in a manner that is well known, where it is desired to effect a joint. The two halved parts d lap, and a hole, e, through each receives the round part b' of the 30 post, which, besides sustaining the arms, serves as a pivot for them. Each halved part d has on its edge, at one side of the pivot-hole e, a shoulder, f, and on the opposite side of the pivot-hole it has a curved rim, g, one end of 35 which forms a shoulder, g', and the other end forms a curved extension, g''. With this construction, when the two halved parts are together on the post b', the free ends of the arms may move toward or spread apart from each 40 other, as indicated in Fig. 1 by broken lines; but the extent of this movement toward each other is limited by the curved extension g'' of each arm coming in contact with the other arm, and the opposite or spreading movement 45 is limited by the shoulder g' of one arm coming in contact with the shoulder f of the other arm. While the shoulders g' and f serve as stops, they also serve, when combined with the round part b' of the post and the spring h, here- 50 go in after mentioned, another important purpose, which will be explained farther on. The two curved extensions g'', besides limiting the movement of the arms C one way, overlap each other, and are in contact and serve as a mutual bearing for the arms. A spiral spring, h,

is suitably secured between the two arms and serves normally to keep them spread apart.

The herein-described combination of the post b', the two arms pivoted on the said post so as to be moved thereon freely up or down 60 and provided with the shoulders g' and f, which come in contact with each other, and the spring h, to spread the arms apart, serve to sustain the arms on the post at any point whereat they may be set. This result is obtained from the 65 fact that while the shoulders g' and f, at one side of the post, prevent the two arms from spreading, the spring at the other side of the post exerts a pressure that tends to spread them, and thereby the pivot-hole e in each 70 arm is caused to bind on the post b' hard enough to sustain the arms.

The free end of each arm is curved and has a bar, i, crosswise of it. These bars serve to spread the mouth of the bag. Each cross-arm 75 i has at its ends points i' to hook into the bag. It will be seen that one cross-arm i will support one side of the bag-mouth and the other arm the opposite side of the bag-mouth, and that the spring h will keep the arms spread 80 and the bag-mouth open. The bottom of the bag may rest on the base A.

Having described my invention, I claim and desire to secure by Letters Patent of the United States—

1. In a bag-holder, the combination, with the post, of the arms C, pivoted thereon and provided with shoulders f, the curved rims g, forming shoulders g' and overlapping curved extensions g'', said arms C also provided with 90 cross-arms i, having pins i', and the spring h, connected to said arms near their pivoted parts, as shown and described.

2. In a bag-holder, the combination of a base, A, an upright post having a round part, 95 b', with two bag-supporting arms, C, both pivoted on said round part and provided with shoulders g' and f, the curved extensions g'', lapped together to limit the movement of the arms, the spring h, serving to keep the arms 100 apart, and the outer ends of said arms C provided with cross-arms i, having pins i', as shown and described.

In testimony whereof I affix my signature in the presence of two witnesses.

JOHN SAURER.
